UNITED STATES PATENT OFFICE.

JESSIE CARR TYNDALL, OF ST. LOUIS, MISSOURI.

DESIGN FOR A TOY BALLOON.

Application filed September 6, 1927. Serial No. 23,308. Term of patent 7 years.

To all whom it may concern:

Be it known that I, JESSIE CARR TYNDALL, a citizen of the United States, residing in the city of St. Louis, in the State of Missouri, have invented a new, original, and ornamental Design for Toy Balloons, of which the following is a specification, reference being had to the accompanying drawings, forming part thereof.

Figs. 1, 2 and 3 are top, side and front views, respectively, of a toy balloon showing my new design.

I claim:

The ornamental design for a toy balloon, as shown.

JESSIE CARR TYNDALL.
